CELL STRUCTURE FOR FOLDING BOXES

Elmer H. Lupton, Ilchester, Md.

Application September 20, 1933, Serial No. 690,251

1 Claim. (Cl. 229—15)

In my co-pending application, Serial Number 673,537, I have shown a folding casing, composed of paper board, with cells arranged in rows within the casing, each cell adapted to receive a bottle and the cells adapted to fold flat when the casing is collapsed. In the structure described in the aforesaid application, the cells in each row are separate parts, united by having their adjacent sides glued together.

10 The present invention relates to a method of making the cells whereby each row of cells is made as a unit from a single blank, the adjacent cells in the row being connected together alternately at their top and bottom edges at creased lines in the blank, whereby the cells may fold against one another and the ends of the cells will be more evenly of the same height than where the cells are made separately and fastened together. Also by this method a saving in 15 labor in the gluing operation is effected, as hereinafter described.

In the accompanying drawings,

Fig. 1 is a plan view of a blank creased and cut to form four connected cells;

25 Fig. 2 is a perspective view of the blank, folded along its longitudinal creased lines and having its lateral edges brought together and fastened, forming a tube;

30 Fig. 3 is a perspective view of the several sections of the tube, partly folded along the transverse crease lines, forming a series of connected cells;

Fig. 4 is a similar view of several series of cells within a folding casing;

35 Fig. 5 is a section on the line 5—5 of Fig. 4, and,

Fig. 6 is a horizontal section through the casing and the cells, partly folded.

Referring first to Fig. 1, A represents a strip 40 of paper board, creased and cut to form four connected cells. The strip has four longitudinal creases, 1, 2, 3 and 4, dividing the strip into four panels, 5, 6, 7 and 8, of equal width, extending longitudinally of the strip, and a narrow longitudinal flap 9 at one side, and divided by transverse cuts and creases into four equal parts, a, b, c and d, of equal length. Thus, the parts a and b are divided by a crease 10 extending across the panel 8 and by cuts 11 in the panels 5, 6 and 7 and the flap 9. The cuts 11 do not entirely sever the panels 5, 6 and 7, but leave short connecting portions 12 in the panels between the parts a and b. Between the parts b and c, the panel 6 is creased transversely, as shown at 10^a, while the other panels and the flap 9 are cut as

shown at 11^a, short connecting portions 12^a being left in the panels. The parts c and d are divided in the same way as the parts a and b by a crease 10^b in the panel 8 and cuts 11^b in the panels 5, 6 and 7 and in the flap 9, the cuts in the panels extending only partly across the same, leaving connecting portions 12^b.

To form the cells, the blank, cut and creased as described, is first folded along its longitudinal crease lines into tubular form, as shown in Fig. 2, and by a single gluing operation the flap 9 of the blank is glued to the margin of the panel 5. Assuming the tube to have been formed as described, in order to complete the unit of four cells, the operator, by twisting the sections 15 a and b slightly in opposite directions, breaks the connecting portions 12 between these sections and in a similar manner breaks the connecting portions between the sections b and c and between c and d. As illustrated in Fig. 3, 20 the section a is then folded along the crease line 10 against the section b; the section c is folded along the crease line 10^a against the opposite side of the section b and the section d is folded along the crease line 10^b against the section c. 25 Thus, the four sections of the tube, in Fig. 2, form a unit of four cells of equal dimensions, the successive cells in the series being connected alternately at their upper and lower ends and standing at the same height when brought together in the casing, as illustrated in Figs. 4 and 5.

In Figs. 4 and 6, three units of four cells each are shown in the collapsible casing E. Thus, one unit is indicated by the reference characters a, b, c and d; another unit is indicated by a', b', c' and d', and the third unit is indicated by a², b², c², and d². Before being placed in the casing, the sides of adjacent cells in a unit may be glued at the ends opposite to those which are integrally connected along the creased lines. Thus, referring to Fig. 3, a smear of glue will connect the upper ends of the sides 8 of sections a and b; the lower ends of sides 6 of sections b and c will be similarly connected, and the upper ends of sides 8 of sections c and d will be similarly connected. Also, before being placed in the casing, the longitudinal crease lines of the cells will be given a set so that the cells in each unit will fold alternately in opposite directions as indicated in Fig. 6. When placed in the casing, the end cells are glued to the sides e so that when these sides are spread apart, in unfolding the casing, the units will straighten out and the cells will be rectangular in cross-section, as shown in 55

Figs. 4 and 5. The sides e' of the casing fold outwardly, as indicated in Fig. 6, and when the sides e are pressed toward one another, the cells fold in zigzag manner and flatten out between the sides e , as described in my co-pending application, hereinbefore referred to. In order to fold in this manner between the opposing sides, it is essential that each row shall be composed of an even number of cells.

- 10 One advantage of the method of construction herein described is that the ends of the cells in each unit are necessarily flush with one another and do not interfere with the closure of the cover portions of the casing, as might occur if the cells were made separately and fastened together, and the labor cost is reduced because the adjacent cells are integrally connected at one end, and these integral connections position the cells so that their

opposite ends may be easily connected by a smear of glue.

What I claim is:

A folding container for bottles comprising an outer casing having opposed folding sides and opposed non-folding sides, and collapsible cells, each rectangular in cross-section when unfolded, arranged in closely adjacent rows between said non-folding sides, each row comprising an even number of cells formed from a single paper-board blank and each cell in a row being integrally connected at one end to the corresponding end of the next cell in the row, and the end cells in some of the rows being attached to said non-folding sides, the successive cells in each row being 15 creased to fold oppositely in zigzag manner. 5

ELMER H. LUPTON.
